SHOE

William F. A. Buehner, New York, N. Y.

Application September 1, 1937, Serial No. 162,025

2 Claims. (Cl. 36—11.5)

This invention relates to improvements in shoes, and particularly to a lady's shoe having parts thereof interchangeable and replaceable so that the color and appearance of the shoe may be changed to suit and conform with the style and color and character of costume or dress, or accessories or the like; and, also to follow or carry out the desires and preferences or whims of the wearer.

10 The primary object of this invention is to provide a shoe structure in which the top and the heel portions can be interchanged and replaced with respect to the sole structure, to thus give different colors and styles and characteristics to 15 the same base or shoe sole portion.

Another object is to so construct and associate and assemble the parts that the top portion can be quickly and easily detached and any number of interchangeable top portions can be provided 20 to be applied or attached with the same speed and facility.

Still another purpose is to provide detachable heel portions together with means for holding and retaining the heel portion in place with respect 25 to the sole portion, to thus permit quick and ready changing of the heel member, and to yet insure that the heel portion will remain in place when the shoe is in use.

Yet a further object is to provide a shoe structure of this character with which upper portions 30 of different sizes and styles can be interchangeably fitted, to thus fit individuals having feet possessed of different characteristics, as for instance a thick or a flat instep portion, and the like.

35 With the above and other objects in view, some of which will be apparent to those skilled in the art, and others inherent in and resultant from the particular construction, my invention includes certain novel features of construction and combinations and arrangements and associations of 40 parts which will be hereinafter set forth in connection with the drawing and then pointed out in the claims.

In the drawing:

45 Figure 1 is a view in perspective showing a shoe constructed according to my invention.

Fig. 2 is a view in side elevation.

Fig. 3 is a top plan view of the shoe.

Fig. 4 is a detail view showing one of the strap 50 members of the shoe upper to fit over and across the forward part of the foot.

Fig. 5 illustrates a strap member cooperating with the member shown in Fig. 4.

Fig. 6 is a detail front elevation of the heel 55 holding clip.

Fig. 7 is a view in front elevation illustrating the detachable heel.

Fig. 8 is a fragmentary perspective view illustrating one of the attaching tabs carried by the 60 sole portion.

Fig. 9 is a fragmentary sectional view to better show the manner of assembling and attaching or securing some of the strap members making up the shoe upper portion.

As illustrated, the shoe sole member 1 is made substantially continuous throughout the sole portion and the instep and heel portions, and this sole member 1 has a lining or finishing cover 2 cemented or sewed or otherwise secured on the upper side thereof. To all intents and purposes, 10 the sole member 1 can be made to follow an outline substantially similar to like portions of an ordinary shoe, and this sole member can be shaped in the arch or instep and in the heel portions to substantially conform to the lines of the 15 foot.

Shoe upper attaching tabs 3 and 4 are integrally secured on opposite sides of the sole portion 1, adjacent to the toe part and rearwardly adjacent to the location of the ball of the foot. 20 Shoe upper attaching tabs 5 are connected with the sole portion 1 in the general location of the normal forward edge of a heel structure. The shoe upper is made up or composed essentially 25 of strap-like members 6, 7, 8 and 9, and a heel strap member 22, detachably connected together and having their ends detachably connected with the attaching tabs 3, 4 and 5.

As shown in Figs. 4 and 5, the strap members 6 and 7 are of substantially equal length and are 30 provided at their ends with portions 11 of a snap fastener adapted to be detachably connected with mating portions 10 of the snap fastener carried by the attaching tabs 3. The strap 7 has in its middle area an extending or stud portion 12 of 35 a snap fastener, and the strap 6 is provided with an opening 13 through which this extending portion 12 of the snap fastener will pass, after the manner illustrated in Fig. 9. The strap 9 has at one end a mating portion 14 of a snap fastener 40 which is fitted to cooperate with the snap fastener portion 12 to hold the two straps 6 and 7 in crossed relation and to dispose the strap member 9 to extend rearwardly therefrom. The free end of this strap member 9 is provided with a 45 portion of a snap fastener and the strap 8 has in its middle area a mating portion of a snap fastener to cooperate with the snap fastener portion on the free end of the strap 9. At its ends, this strap portion 8 has openings similar to opening 50 13 to receive the extending studs of snap fastener portions 10 on the attaching tabs 5.

The heel strap member 22 has at its ends snap fastener portions 23 which fit or snap and hold on the portions 10 of the tabs 5 to thus connect and 55 hold the heel strap member and also hold the ends of strap 8 in place.

Obviously, the strap portions 6, 7, 8, 9 and 22 can be made of any desired shape or configuration and of any suitable material, and can be 60

decorated or ornamented and can be colored to suit different requirements of use and different tastes or desires of the wearer. Also, the strap portions can be made of various materials, as for example leather or fabric where a maximum of 5 yieldability or stretchability is not required, or of elastic material or the like, where elasticity is necessary or desirable.

The heel portion of the sole member 1 has a 10 heel securing clip 16 rigidly connected therewith and adapted to receive and hold the heel member 15. This heel clip 16 is provided on opposite sides with the inwardly disposed and opposed ribs or flanges 17 and 18, adapted to fit and hold within 15 the grooves or ways 19 and 20, when the heel member 15 is located on the lower side of the sole portion and is moved rearwardly between these flange portions 17 and 18. To prevent rearward displacement of the heel member 15, I provide a 20 retaining flange 21, and to insure that the heel member 15 will be held substantially rigidly in place, I may make the flange portions 17 and 18 slightly yieldable to permit the heel portion to be forced into place and to then retain this heel 25 portion or member 15 against casual or accidental displacement. Of course, the heel member 15 can be made of any desired material or can be finished in any desired and approved manner.

In the use of my improved shoe structure, the 30 fastener portions 11 of the several strap members can be retained on the fastener portions 10 on the attaching tabs 3, 4 and 5, and the shoe upper can then be entirely removed, to be replaced at any desired time, or leaving the shoe 35 sole portion available for fitting and attachment of a shoe upper structure of different character or color or style or material, as may be desired by the individual user and wearer. Also, the heel member 15 can be moved forwardly to disengage 40 the attaching portions of this heel member from the attaching portions of the heel clip 16, and then the heel can be readily removed, to be replaced at any time desired, or to have substituted therefor a heel of different size or height, or of 45 material, or color, or finish, or other characteristics.

As has been stated or intimated, the strap portions of the upper can be made of any desired and approved material, of any color and finish, or 50 other characteristics can be embodied to suit the desires and requirements of individual distributors or merchandisers, and of different wearers or users. For example, a shoe store or dealer can have a plurality of sole portions 1 of standard and perhaps neutral appearance, or of various hues or colors, and then when individual requirements are to be met, the accessory portions, consisting of the straps 6 and 7, 8, 9 and 22 and the heel 15, can be supplied and assembled. If 55 the strap portions 6 and 7 and 8 be made of different lengths, individual fittings of considerable accuracy can be made to accomplish a neat and accurate fit upon a full or slender foot, and by providing straps 22 of different lengths and 60 widths neat and accurate fittings at the heel can be accomplished. Further, by making these strap portions of elastic or yielding material, a self conforming and self fitting upper structure can be provided. The length of the strap 9 can be 65 varied to throw the strap 8 higher or lower across the top of the instep of the foot, and in other manners variation of the length and connection of the strap portions can be made to suit and fit 70

the particular foot of the individual wearer. With the heel members 15 made and constructed to be readily attached and detached, it is possible to change the heel to suit the color or other characteristics of a changed upper portion, and it will be appreciated that heel members 15 of different heights and different tread sizes and different shapes or designs can be interchangeably fitted and used.

Although snap fasteners are particularly de- 10 scribed and illustrated, other forms and types of fastenings can be used, the primary purpose being to provide fastenings that allow and facilitate ready detachment and attachment and interchanging of the strap members.

While I have herein shown and described only certain specific embodiments of my invention and have suggested only certain possible modifications, it will be understood and appreciated that many other changes and variations can be made 20 in the form, construction, arrangement, assembly and association of the parts, in the materials used, and in other respects, without departing from the spirit and scope of my invention.

I claim:

1. A shoe comprising, a sole member, a plurality of upper attaching tabs carried in pairs at opposite edges of the sole member with a forward pair adjacent to the toe end of the sole and the intermediate pair adjacent to the forward 30 end of the instep and a rear pair adjacent to the rear of the instep, fastener portions on each of the tabs, a pair of toe arch straps associated in diagonally crossed relation, mating fastener portions on said straps detachably connecting the 35 crossed straps each with one end attached to a forward tab and the other end attached to one of the intermediate tabs, a transverse instep strap, fastener portions on the transverse instep strap detachably connecting said strap with the 40 rear attaching tabs to arch over the instep in front of the ankle, and a longitudinal instep strap connected at its forward end with said toe arch straps substantially at the point of crossing of said straps and connected at its rear end with the arched up portion of the transverse instep 45 strap.

2. A shoe comprising, a sole member, a plurality of upper attaching tabs carried in pairs at opposite edges of the sole member with a forward pair adjacent to the toe end of the sole and the intermediate pair adjacent to the forward end 50 of the instep and a rear pair adjacent to the rear of the instep, fastener portions on each of the tabs, a pair of toe arch straps associated in diagonally crossed relation, mating fastener 55 portions on said straps detachably connecting the crossed straps each with one end attached to a forward tab and the other end attached to one of the intermediate tabs, a transverse instep strap, fastener portions on the transverse instep strap detachably connecting said strap with the rear 60 attaching tabs to arch over the instep in front of the ankle, a longitudinal instep strap connected at its forward end with said toe arch straps substantially at the point of crossing of said straps and connected at its rear end with the arched up portion of the transverse instep strap, and a heel strap detachably connected at its ends with 65 said rear attaching tabs and arching upwardly 70 to catch over the rear of the heel of a wearer.

WILLIAM F. A. BUEHNER.
